Patented Sept. 6, 1921.

Arthur M. Lisby
PROPRIETOR

UNITED STATES PATENT OFFICE.

ARTHUR M. LISBY, OF NEW YORK, N. Y.

DESIGN FOR A BUTTON.

58,921.

Specification for Design.

Patented Sept. 6, 1921.

Application filed April 2, 1920. Serial No. 370,895. Term of patent 14 years.

To all whom it may concern:

Be it known that I, ARTHUR M. LISBY, a citizen of the United States, residing at New York, county of New York, and State of New York, have invented a new, original, and ornamental Design for Buttons, of which the following is a specification, and reference being had to the accompanying drawing, forming part thereof.

The figure is a plan view of a button showing my new design.

I claim:

The ornamental design for a button as shown.

ARTHUR M. LISBY.
